ACTION MECHANISM FOR A POPPET VALVE

George M. Braun, 2729 N. Summit Ave.,
Milwaukee, Wis.

Filed Nov. 27, 1959, Ser. No. 855,742

6 Claims. (Cl. 123—90)

My invention relates to an improvement in action mechanism for a poppet valve.

More particularly stated, my invention relates to an improvement in valve action mechanism not only providing for improved control for quiet and efficient opening of a poppet valve, but also providing for resilient, but substantially positive closing action.

Furthermore, my invention makes special provision for resiliency and adjustment of a valve action mechanism in a compact form adapted to be mounted in a chamber open at one side relative to the usual location of a valve action mechanism.

In the drawings:

Fig. 1 is a vertical sectional view showing fragmentarily that portion of an internal combustion engine including my valve action mechanism; the section being taken in a plane normal to the axis of the cam shaft.

Fig. 2 is a section on line 2—2 of Fig. 1.

Fig. 3 is an exploded view of a rocker arm and spring therefor in accord with my invention.

Fig. 4 is a section on line 4—4 of Fig. 1.

Fig. 5 is a view somewhat comparable to Fig. 1, but showing an alternative form of my invention.

Fig. 6 is a section on line 6—6 of Fig. 5.

Fig. 7 is a section on line 7—7 of Fig. 5.

Fig. 8 is a side elevation of a rocker arm in a second alternative form of my invention, a portion of the rocker arm being broken away to exhibit the construction through a vertical section.

Fig. 9 is a section on line 9—9 of Fig. 5.

An environment for my invention includes a cylinder block 15 fragmentarily shown in the drawings and a cylinder head 16, portions of which are designed to provide a firing chamber 17 into which fuel mixtures may be fed or from which exhaust gases may be released by a poppet valve 18 including a valve head 19 and valve stem 20. These valve parts 19 and 20 are guided in their limited reciprocal motion by valve guide 21 carried by a wall 22 forming part of the cylinder block. Above the wall 22 there is a chamber or passageway 23 for gases and at 24 there is a top wall of this chamber or passageway which is provided with a port 25 to be opened and closed by reciprocation of valve 18.

Usual provisions for coolant in jacketed portions of the block 15 and of the head 16 are shown at 28 and 29 respectively.

Some of the important valve action mechanism to be described below is housed in a chamber 30 lying beneath wall 22 and above floor 31 of chamber 30. Below floor 31 is crank case 32 adjacent the top of which extends cam shaft 33 for the operation of the valve mechanism. Floor 31 therefore provides a mounting for a cam follower 35 fitted for vertical reciprocation as shown clearly in Figs. 1 and 2.

The lower end of stem 20 of valve 18 is threadedly engaged with cam follower 35 and there is a lock nut 37 with special lock nut 37 to make it possible to establish positive adjustment of the length of the combined stem

2

and follower. Cam 33 is provided with cam lobe 38 of such configuration as to properly raise the cam follower 35 for the opening of valve 18 in timed relation for the operation of the engine with which this valve action is concerned.

It will be noted that along the stem 20 and with respect to the cam follower 35 there is no spring to close the valve and it will be noted that in the cam and cam follower action respecting the cam lobe 38 on cam 33 there is only provision for positive opening of the valve. The closing of the valve is accomplished by the valve action mechanism now to be described.

For the chamber 30 there is a closure plate 40 to close the opening at 41, and lying between plate 40 and the valve stem 20 there is a rocker arm shaft 42. This rocker arm shaft provides a mounting for rocker arm 45, one end of which is bifurcated at 46 so that the two portions of it at 47 and 48 respectively may be disposed with the stem 20 therebetween. At the other end of the rocker arm 45 there is an adjustably mounted resilient push-rod connection 50. This assembly includes a rocker spring 51 assembled with the rocker arm 45 as shown in Figs. 1 and 3 where it will be seen that the rocker arm itself is effectively made unitarily including a spring back-up arm 52 and a rocker bearing sleeve 53. The spring 51 in released position has contours shown in Fig. 3 to provide for ready assembly with a somewhat cylindrical portion 54 to lie about sleeve 53. In the extended spring arms, 55 and 56, are apertures to receive adjusting stem 57 of the push-rod connection 50. Stem 57 is threaded and is provided with nuts and lock nuts at 58 and 59 to provide for adjustment of spring 51 as will be described below and it will be noted that the lower end of stem 57 is hemispherical so as to bear against the socketed end 35 of valve closer stem 60. This valve closer stem with its valve closer cam follower 61 is reciprocably mounted through the floor 31 of chamber 30 in such relation to cam shaft 30 that, with roller 62 in position at the lower end of cam follower 61 there is an anti-friction relationship with valve opening cam lobe 65 forming part of the cam shaft 33. This cam lobe has its position close to cam lobe 38 but slightly axially off set therefrom and it will be noted that the rocker arm 45 is so shaped as to offset the bifurcated end 46 from the aligned cam lobe 65 and the valve closing stem 60. (See Fig. 2.)

Assuming that the parts thus far described are to be assembled in the first instance, stem 20 will be inserted through guide 21 prior to the time that the cylinder head 16 is applied to cylinder block 15. Obviously, nuts and lock nuts such as 36 and 37 are not applied to the stem 20 until the valve stem is approximately in position for threaded engagement with its cam follower 35. Prior to the time that the cam shaft 33 is assembled with the engine, cam follower 35 is inserted through the opening in the floor 31 provided therefor and it is then possible to threadly engage stem 20 with the cam follower. Later, when the cam shaft 33 is assembled with the engine, adjustment of the stem and cam follower will be so made and locked that the valve will be in fully closed position 60 when the cam follower 35 is approximately in bearing relation to the concentric smallest diameter of the cam shaft 33 but allowing the usual clearance for expansion.

Cam follower 61 is then placed in position as shown in Figs. 1 and 2, the rocker arm 45 is placed in position 65 upon rocker arm shaft 42 and when push-rod stem 60 is placed in position in the cam follower 61 as shown in Fig. 1 push-rod connection 50 is assembled upon the rocker arm and in proper relationship to spring 51. The proper relationship in this regard is attained when the bifurcated end 46 of lever 45 is brought to bear upon valve closing washer 67, which is rigidly secured to stem 20. This proper relationship, when valve 18 is closed, is

determined by the proper spring pressure of the end 56 of spring 51 against the nut and lock nut assembly 59 in position upon stem 57. With all the lost motion taken out of the relationship of the various parts, a firm degree of pressure must be exerted by bifurcated arm 46 of rocker arm 45 when the roller 62 is on the concentric largest diameter of cam 65. This determines that the spring pressure is exerted to keep the valve head 19 firmly upon its seat in closed relationship to the aperture 25. Then when the cams are rotated as will be described below, there is a cam valley at 66 in cam 65 in proper timed relationship to the position of cam lobe 38 to open and close the valve 18 as the cam shaft 33 rotates.

The alternative construction shown in Figs. 5 to 9 inclusive is quite similar to that described above, except that the spring provided at 51 finds its functional equivalent in a spring 75 in the form of a helical cylindrical spring disposed between a cam follower shelf 76 on cam follower insert 77 carried by cam follower 35. Then at 78 there is a floating washer apertured to receive stem 20 of valve 18 so that the floating washer may reciprocate upon the stem under the control of the bifurcated end 46 of rocker arm 80. This rocker arm 80 is substantially rigid since the features of resiliency desired for valve closing operations are provided by spring 75. This means that a push-rod assembly 85 merely requires a threaded adjustment without any direct spring accommodation relative to the rocker arm at that point. It will be noted as shown in Figs. 5 and 6 that a cam shaft 90 is provided with two cams relative to each valve. Cam 91 has a continuous concentric lobe except for the relieved "valley" at 92. Whereas cam 93 has a relatively short lobe 94 and a continuous concentric "valley" 95 extending around the rest of the circumference. The relationship of the two cams is shown most clearly in Fig. 5 where it will be seen that in view of the number of degrees by which the valve stem 20 is offset from the push-rod stem 60 of the "valley" at 92 provides a degree of relief when the lobe 94 opens the valve, but when the valve is to be closed the lobe 94 has passed the cam follower 35 to permit of the valve closure and the push-rod 60 has been thrust upwardly to the left as seen in Fig. 5 whereby to bring rocker arm pressure on spring 75 to urge the valve to closed position.

To provide shock resistance for rocker arm 80 the rocker arm may be provided as shown in Fig. 8 in an alternative construction 96 wherein a relief spring arm 97 is cast "integrally" with the material of the rocker arm 96 and this spring is apertured at 98 to receive push-rod assembly 85.

I claim:

1. In an internal combustion engine having a cylinder block provided with a chamber for gases and an opening for gas passage relative to said chamber; a reciprocable stemmed poppet valve having a head positioned to close

or open said opening, a valve action chamber positioned adjacent the chamber for gases with a wall therebetween including a guide for the stem of the valve extended across the valve action chamber; a walled crank case, one wall of which is positioned to provide a floor for said valve action chamber equipped with divergent guides for cam followers; cam followers in said guides; a cam equipped cam shaft positioned in the crank case adjacent said cam followers, a valve action lever and shaft therefor in the valve action chamber adjacent said stem, and action transmitting connection respectively including said cam followers between the cam equipped cam shaft and the stem, and between said cam shaft and said lever for substantially positively opening and closing said valve.

2. The engine of claim 1 in which the lever includes a stiff spring providing slight resilience in the closing of said valve.

3. The engine of claim 1 in which the stem is provided with a spaced apart fixed shelf and floating washer with a compression spring therebetween, and the lever is positioned to bear upon the washer in a direction to compress the spring in a valve closing direction.

4. The engine of claim 1 in which the valve action chamber is provided with an openable inspection cover and the connections between the lever and the cam shaft are adjustable and positioned within service distance of said cover.

5. A valve action mechanism for a stemmed poppet valve provided with a valve action shelf fixedly mounted to the stem of the valve, cam means opposite the end of the stem in position to bear thereupon in a valve opening direction, cam follower means positioned to be actuated by said cam means in an angular direction divergent from said stem, a lever mounted to a lever shaft positioned within the angle, one end of the lever extending into position against the shelf and the other end of the lever having a connection with the divergent cam follower means, one of said ends of said lever comprising a rigid spring back-up arm and two spaced spring arms with a wrap-around spring intermediate portion integral with said spring arms, said wrap-around portion being positioned about said lever shaft.

6. The valve action mechanism of claim 5 in which a sleeve is positioned between the lever shaft and said wrap-around spring intermediate portion.
